UNITED STATES PATENT OFFICE.

HENRY WURM, OF CLEVELAND, OHIO.

ROPE CLAMP.

Application filed March 23, 1925. Serial No. 17,557.

To all whom it may concern:

Be it known that I, HENRY WURM, a citizen of the United States, residing at Cleveland, in the county of Cuyahoga and State 5 of Ohio, have invented certain new and useful Improvements in Rope Clamps, of which the following is a specification.

The present invention relates to certain new and useful improvements in cord and 10 rope clamps, and has for its object to provide a device of this character which embodies novel features of construction, whereby it can be inexpensively formed from wire and will tightly grip a cord or rope so that 15 the cord or rope can be secured without the need of a knot.

Further objects of the invention are to 20 provide a device of this character which is simple and inexpensive in its construction, which can be readily mounted in position, and which will tightly grip a cord or rope without injuring the same.

The invention further contemplates the 25 provision of a device of this character which can be readily formed from a single length of wire, and which embodies means whereby the cord or rope can be readily released and disengaged when desired.

While one preferred embodiment of the 30 invention has been shown on the drawing and will be described in the specification for illustrative purposes, it will be understood that I do not restrict myself to the exact construction shown, and that many 35 modifications and changes can be made in the details of construction without departing from the spirit of the invention.

For a full understanding of the invention reference is to be had to the following 40 description and accompanying drawings, in which,

Figure 1 is a front elevation of a rope 45 clamp which is constructed in accordance with the invention, the rope being shown by full lines in the position assumed when it is gripped, and by dotted lines in the position assumed when it is released.

Figure 2 is a side elevation of the rope clamp.

Figure 3 is a transverse sectional view on the line 3—3 of Figure 1, the rope being omitted.

Figure 4 is a vertical sectional view on the line 4—4 of Figure 1, the rope being omitted.

The rope clamp shown on the drawings is intended to be formed from a single length of stiff wire. An intermediate portion of the wire is looped to form a jaw 1, and the opposite ends of the loop terminate 60 in inwardly extending reversely curved helical portions 2. These reversely curved helical portions 2 cross each other and terminate in substantially parallel arms 3 which form the opposite jaw of the device. A pair of 65 V-shaped notches 4 are provided on opposite sides of the intersection of the reversely curved helical portions 2, as indicated by Fig. 3, and the rope is clamped by drawing portions thereof tightly into these 70 V-shaped notches 4 so that they are securely gripped by the wire.

The arms 3 may be provided with any suitable means for attachment to a post or support. As shown on the drawings, the 75 ends of the arms 3 are provided with laterally bent portions 5 which are engaged by the staples 6. The staples can be driven into the post or other support and provide a pivotal mounting for the rope clamp so 80 that the latter can swing about the laterally bent portions 5 of the wire as an axis and adjust itself to the tension or pull of the 85 rope. The laterally bent portions 5 of the wire may terminate in hooked portions 7, which provide rope guides and are arranged 90 in the plane of the arms 3. These hooked guides 7 are arranged opposite the flared mouths of the respective V-shaped notches 4 and when it is desired to disengage the rope 95 from one of these notches, the rope can be carried around the hooked member 7, as indicated by dotted lines on Figure 1, whereupon a pull on the free end of the rope will serve to disengage the rope from the notch. 100 The hooked guides 7 may also be used to engage the rope when it is merely desired to loosely engage an intermediate portion of the rope without clamping or fastening the same.

The rope clamp can be inexpensively formed from a single length of wire and the construction is such that it can be left in an exposed position without danger of injury, there being no wood parts to cause trouble 105 by swelling or splitting when exposed to the weather.

In order to grip the rope it is merely necessary to insert a portion thereof between the looped jaw 1 and the jaw provided by 110

the arms 3, whereupon a pull upon the ends of the rope will draw the same into the V-shaped notches 4 and cause them to be securely gripped thereby. The construction 5 is such that the harder the pull upon the rope the more securely it will be gripped and there is no danger of the rope becoming accidentally released. The hooked guides 7 provide means for readily releasing the 10 rope from the clamp when such is desired and these hooked guides can also be utilized when it is merely desired to draw the rope loosely around a hook member without fastening or clamping the same.

15 Having thus described my invention what I claim as new and desire to secure by Letters Patent is,

1. A rope clamp formed of a single length of wire and comprising a looped jaw, 20 a pair of spaced arms forming a complementary jaw and crossed strands connecting the arms and looped jaw, said crossed strands providing V-shaped rope gripping notches on opposite sides of their intersection 25 and the arms terminating in laterally bent portions, a base, and pivot members projecting from the base and pivotally receiving the laterally bent portions of the

arms, whereby the rope clamp is free to swing with respect to the base. 30

2. A rope clamp formed from a single length of wire and including a looped jaw, arms forming a complementary jaw, crossed strands connecting the looped jaw and arms and providing V-shaped rope engaging 35 notches on opposite sides of their intersection, and rope guides at the ends of the arms said rope guides being arranged opposite the mouths of the respective rope engaging notches. 40

3. A rope clamp formed from a single length of wire and including a looped jaw, a pair of arms forming a cooperating jaw, reversely curved helical portions connecting the looped jaw to the arms said helical 45 portions intersecting each other and providing V-shaped rope engaging notches on opposite sides of the intersection, and rope guides at the ends of the arms, said rope guides being arranged opposite the mouths 50 of the V-shaped notches and providing a means for disengaging the rope from the notches.

In testimony whereof I affix my signature.

HENRY WURM.
